UNITED STATES PATENT OFFICE.

VOLNEY W. MASON, OF PROVIDENCE, RHODE ISLAND.

WINCH.

No. 901,719.

Specification of Letters Patent.

Patented Oct. 20, 1908.

Application filed August 23, 1905. Serial No. 276,055.

To all whom it may concern:

Be it known that I, VOLNEY W. MASON, a citizen of the United States, and a resident of Providence, in the county of Providence and State of Rhode Island, have invented a new and Improved Winch, of which the following is a full, clear, and exact description.

This invention relates to winches or crabs, such as used by riggers and others for hoisting heavy weights.

The invention conveniently forms a part of or is attached to a derrick.

The object of the invention is to simplify the construction of a winch so as to reduce the amount of gearing necessary and to provide improved means for applying a brake-band.

A further object is to provide a convenient arrangement whereby the virtual length of the lever for operating the winch may be increased or diminished, as desired.

The invention consists in the construction and combination of parts to be more fully described hereinafter and definitely set forth in the claims.

Reference is to be had to the accompanying drawings forming a part of this specification, in which similar characters of reference indicate corresponding parts in all the figures.

Figure 1 is an end elevation of a winch constructed according to my invention, and representing a portion of a derrick to which the winch is attached; Fig. 2 is a front elevation of the winch, and showing a portion of the derrick; Fig. 3 is a longitudinal central section on the line 3—3 of Fig. 1, and passing through the drum of the winch and the bearings therefor; this view also shows a portion of the derrick in cross section; Fig. 4 is a section taken on the line 4—4 of Fig. 1, and showing contiguous parts broken away; Fig. 5 is a vertical section taken at the brake-band lever, and illustrating the manner in which the lever operates to apply the brake or release the same; contiguous parts in this view are represented as broken away; and Fig. 6 is a cross section taken on the line 6—6 of Fig. 5.

Referring more particularly to the parts, 1, 1 represent oppositely disposed stringers of a derrick to which a winch 2 is attached. The winch comprises a substantially rectangular frame 3 which is bolted to the stringers, as shown, providing a rectangular opening

or space 4, in which a drum 5 is rotatably mounted.

Referring especially to Fig. 3, in order to support the drum, the shaft 6 thereof is rotatably mounted in suitable bearing-caps 7, which caps are attached by bolts, as indicated, to the frame 3. Between the bearings, which are preferably provided with rollers 8, is provided a drum 5. This drum comprises a cylindrical sleeve 10 of enlarged diameter with respect to the shaft 6, and this sleeve is formed integral with an outer head 11.

The main head 12 of the drum is preferably provided on its inner face with a boss 13, which sets into the bore 14 of the sleeve 10, as indicated, and this main head is rigidly secured to the body of the drum by means of suitable bolts 15. This main head 12 is, of course, of circular form, and is provided at its outer extremity with a laterally projecting flange 16. The outer face of this flange is smooth, and is adapted to have the brake-band applied thereto, so that the head 12 constitutes a brake-wheel. The inner side 18 of the flange 16 is formed with teeth 17, so that this head constitutes an internal gear, as will be readily understood.

At a suitable point in the frame 3, a stub-shaft 18 is provided, the same being rotatably mounted in a suitable bearing 19; this bearing is preferably provided with rollers 20, as indicated. The inner extremity of the stub-shaft 18 carries rigidly a pinion 21, which meshes with the aforesaid teeth 17, enabling the rotation of the stub-shaft 18 to be transmitted to the drum. The central portion of the outer end face of the stub-shaft 18 is removed, as indicated at 22, and at this point the stub-shaft is provided with alining transverse slots 23, as indicated most clearly in Fig. 4. These slots 23 constitute a guide for a hand-lever 24, the body whereof is slidable through the slots, as will be readily understood. This hand-lever 24 is provided at its extremity with a handle 25, so that it constitutes a crank, enabling the pinion 21 to be rotated when desired. I provide an arrangement for enabling the lever 24 to be held in different adjusted positions. For this purpose, the extremity or end face of the stub-shaft 18 is provided with an enlarged bore 26, which is concentric with a bore 27 of smaller diameter. In the bore 27 a pin 28 is mounted, the same having a

head 30 disposed in the large bore 26. Under the head 30 a helical spring 31 is placed, which thrusts against the bottom of the bore 26, tending to force the pin outwardly. The outer face of the head 30 is formed with a conical knob or point 32, and the spring 31 operates to hold this point against the inner face of the lever 24. The inner face of the lever is provided with a plurality of conical recesses 33, which are adapted to be engaged by the point, as will be readily understood, so as to lock the lever against accidental displacement. In operating the crank, however, it should be understood that when a sufficient force is exerted tending to slide the lever longitudinally, the pin 28 will not operate to prevent such movement; and when the lever is slid along as suggested, to shorten or lengthen the virtual lever-arm the spring 31 will operate to force the pin into the next recess 33 as it passes the pin. In this way, arrangement is made for locking the lever against accidental displacement, and at the same time I am enabled to shift the lever so as to increase or decrease the leverage, when desired. Such an arrangement as this is often desirable, where changes in the character of the movement must be made. This movement is also advantageous where a load is to be allowed to run down; in this instance it is desirable to shorten the arm of the lever 24 so as to reduce the danger from accident in its rotation.

As indicated most clearly in Figs. 1 and 2, at a suitable point on the frame 3 is provided a pair of ears 34, between which is pivoted a block 35. This block affords means for attaching a brake-band 36, said 40 brake-band being provided with a bolt 37 at its extremity, which passes through the block, said bolt having nuts 38 which screw respectively against the opposite faces of the block, so as to secure the brake-band, as will be readily understood. The body of the brake-band is curved so as to correspond to the curvature of the flange 16, and lies adjacent to the outer face thereof, as indicated most clearly in Fig. 1. The lower extremity of the band is rigidly attached to a shackle 39, which preferably curves inwardly, as shown, at its extremity. This shackle 39 is provided with a central slot 40, as shown most clearly in Figs. 5 and 6. At a convenient point the frame 3 is provided with oppositely disposed ears 41, between which a brake-lever 42 is mounted on a suitable pin 43. This brake-lever is a bell-crank lever, the short arm 44 whereof attaches by means of a pin 45 to the extremity of the shackle 39. The long arm 46 of the brake-lever projects downwardly and passes through the slot 40.

Referring to Fig. 5, it will be seen that the curvature of the shackle 39, referred to

above, results in throwing the pin 45 normally on the opposite side of the pin 43, and opposite to the extremity 47 of the brake-band which is attached to the shackle. When the parts are in the relation shown in Fig. 5, the brake-band 36 is not pressed against the face of the flange 16. When it is desired to apply the brake, it is only necessary to pull the lever-arm 46 upwardly into a position such as that shown in Fig. 1. As this movement progresses, the short arm 44 moves downwardly and operates to pull or stretch the brake-band. When the arm arrives at substantially the position shown in Fig. 1, the maximum tension in the brake-band will exist. When the lever arrives beyond its dead center it engages the extremity or edge of the slot 40 in the end of the shackle. In this way, the shackle and lever 46 coöperate to maintain the tension brought about in the brake-band.

In order to facilitate the attachment of the cable 48 to the drum, I provide inclined openings 49 and 50 at the heads 11 and 12. These openings pass through the outer faces of the heads, and communicate with the bore 14 of the drum body. At the same time they are formed so as to intersect the angle between the heads and the body of the drum, and in this way openings 51 and 52 are formed, which lead from the outer faces of the drum body to the interior thereof. This arrangement of openings is highly advantageous, as it enables the cable to be brought out to the face of the body of the drum at either extremity thereof, and also enables the attached end of the cable to be secured to either head of the drum. I prefer to attach the fixed end of the cable to the inner face of the head 12 by means of a suitable clip or plate 53, as indicated in Fig. 3.

In order to facilitate the placing of the cable in position, the body or sleeve 10 of the drum is preferably provided near its middle point with a longitudinally disposed slot 54 which facilitates the insertion of an instrument such as a spike, which will enable the cable to be advanced along the shaft. Needless to say, this slot 54 is placed in longitudinal alinement between the openings 49 and 50.

Having thus described my invention, I claim as new and desire to secure by Letters Patent:

1. In a winch, in combination, a frame, a lever mounted on said frame, a drum, a brake-wheel rotating with said drum, a brake-band coöperating with said brake-wheel, a shackle attached to the extremity of said brake-band and attached to said lever, said lever affording means for tightening said brake-band on said wheel, and means whereby said lever may engage said shackle to limit the movement thereof and lock said band.

2. In a winch, in combination, a brake-wheel, a brake-band co-operating therewith, a frame, a lever mounted on said frame, and a shackle attached to said brake-band and having a slot receiving said lever, said lever affording means for tightening said brake-band, the edge of said slot affording means for arresting the movement of said lever to lock said band.
- 10 3. A winch-drum adapted to have a cable wound thereon and presenting a body of reduced diameter, heads at the extremities thereof, said body having a longitudinal bore, and inclined openings at said heads 15 passing from said bore to the outer faces of said heads, said openings being disposed at the intersection of said heads with said body, whereby other openings are formed on
- the outer surface of said body adjacent to said heads.
4. A winch-drum having a body of reduced diameter and enlarged heads at the extremities thereof, said body having a longitudinal bore, and openings adjacent to the inner faces of said heads and opening communication from said bore, said body further having a slot disposed substantially in alinement between said openings.

In testimony whereof I have signed my name to this specification in the presence of 30 two subscribing witnesses.

VOLNEY W. MASON.
